UNITED STATES PATENT OFFICE.

HERMAN J. SANDER AND ALBERT J. BREISTER, OF FOND DU LAC, WISCONSIN.

PLAYING-CARD HOLDER.

Application filed April 26, 1928. Serial No. 273,049.

This invention is a novel combination playing-card holder, ash tray, and cigarette holder; and the principal object thereof is to provide a novel, simple and efficient com-

60 slightly on an arc of a circle between the back and the thumb portion, hereinafter described, in order to yieldingly retain the cards in the holder.

5 combined playing-card holder adapted to yieldingly retain a "hand" of playing-cards in opened arranged position while permitting the individual cards of the hand to be separately extracted therefrom, the base of the 10 holder forming an ash tray provided with cigar or cigarette holding grooves.

65 Back 1 is mounted on the upper end of a standard 2 which may, if desired, be formed integrally with the back 1 or made separately and attached thereto in any desired manner so as to support the back 1 in vertical position. In the drawing the support 2 is shown to be a continuation of the middle finger portion 1^b, and is attached to the center of a concave-convex dish shaped base 3 of sheet metal preferably by means of a soldered 70 flange 2^a.

15 Another object of the invention is to provide a stamped metal playing-card holder simulating a human hand, and embodying 75 certain novel features of construction to facilitate retention of the playing-cards therein when the cards are in open arranged position, the cards being retained in the holder by the tension formed by bending the cards 20 on an arc between the "thumb and finger" portions of the holder; and suitable means being provided for preventing the "hand" of cards from opening-up beyond a predetermined amount.

80 The central portion of base 3 is raised or convexed as at 3^a and is provided with a downwardly pressed groove 3^b therein for the reception of a cigar or cigarette which 75 may be placed in groove 3^b to prevent rolling, and the periphery 3^c of the base 3 is dished or rolled upwardly to provide a suitable ash tray.

25 Other minor objects will be hereinafter set forth.

85 The lower end of the index finger portion 1^a is elongated and the projecting portion bent back diagonally as at 1^f across the front face of back 1 to form a yielding thumb portion 1^g closely overlying the adjacent portions of the fingers 1^a, 1^b and 1^c to yieldingly retain 90 the cards C in position in the holder. Bend 1^f is disposed at one lower corner of the back 1 substantially opposite the upper end of standard 2, and the opposite lower corner of back 1 namely the base of the little finger 95 portion 1^d is flanged outwardly as at 1^h, the bend 1^f and flange 1^h forming limits to prevent the outermost cards from dropping out 85 of the holder.

35 In said drawings:—

95 In use, the "hand" of cards is opened out in the customary arranged position and the cards inserted between back 1 and the yieldable thumb 1^g, the arranged cards being retained primarily by the tension formed by bending the cards on an arc between the index finger 1^a, little finger 1^d, and thumb 1^g, instead for primarily by the spring tension of the thumb 1^g alone. In our device the thumb 1^g need not actually touch the back 1. The bend 1^f forms a limit for the opening 100 movement at the left hand lower corner of the back, and the flange 1^h forms the corresponding limit at the right hand lower corner of the back 1. The "hand" may thus be held in convenient position in the holder and 105 the cards C readily removed therefrom one at a time during playing of the game; and

40 Figure 2 is a section on the line 2—2, Figure 1.

110 As shown in the drawings, our novel playing-card holder preferably comprises a back 1, preferably stamped from sheet metal and formed to simulate the inner surfaces of the four fingers 1^a, 1^b, 1^c and 1^d of a human hand in the customary position for holding a "hand" of playing-cards C in opened arranged position.

45 In the drawing, 1^a represents the index finger; 1^b the middle finger; 1^c the third finger; and 1^d the little finger; and preferably the entire back 1 is formed slightly concave, as shown in Fig. 2 so that fingers 1^a and 1^d project outwardly beyond the middle finger 1^b so as to cause the arranged cards to be bent

50

the base 3 forms a convenient cigar holder and ash tray as well as a base for the card holder.

The entire article may be conveniently 5 made of stamped metal and any desired finish may be given thereto such as an enameled, bronzed, nickelized, or other finish.

We do not limit our invention to the exact 10 form shown in the drawing for obviously changes may be made therein within the scope of the claims.

We claim:—

1. A playing-card holder comprising an 15 arcuate stamped sheet metal back, a yieldable thumb member extending from one lower corner of the back and bent to extend diagonally across the concave face of the back; the opposite lower corner of the back being flanged outwardly; and means for supporting the 20 back.

2. A playing-card holder comprising an arcuate sheet metal back stamped to simulate the fingers of a human hand; a yieldable thumb member extending from one lower corner of the back and bent to extend diagonally across the concave face of the back; the opposite lower corner of the back being flanged outwardly; and means for supporting the back. 25

3. A playing-card holder comprising an 30 arcuate sheet metal back stamped to simulate the fingers of a human hand; a yieldable thumb member extending from one lower corner of the back and bent to extend diagonally across the concave face of the back; the opposite lower corner of the back being flanged outwardly; a dish shaped base; and an upright connecting the back and base. 35
